UNITED STATES PATENT OFFICE.

DAVID I. MILLER, OF SHEFFIELD, ALABAMA.

BLAST-FURNACE-CHARGING APPARATUS.

No. 888,723.

Specification of Letters Patent.

Patented May 26, 1908.

Application filed August 30, 1907. Serial No. 390,796.

To all whom it may concern:

Be it known that I, DAVID I. MILLER, a citizen of the United States, residing at Sheffield, in the county of Colbert and State 5 of Alabama, have invented certain new and useful Improvements in Blast-Furnace-Charging Apparatus; and I do hereby declare the following to be a full, clear, and exact description of the invention, such as 10 will enable others skilled in the art to which it appertains to make and use the same.

My invention relates to that class of apparatus commonly employed for transferring blast furnace charges from the ground or 15 stock floor to the charging floor and for uniformly distributing the charges in the hopper of the blast furnace.

Among the several objects accomplished by my apparatus are the saving of time and 20 the minimizing and facilitating of the manual labor required.

In an endeavor to employ a stock car with a charging bridge track and an elevator track section, much labor is required, time lost and 25 difficulty experienced in securing such an alinement of the elevator track section and bridge track as will permit the transfer of the stock car from the one to the other. In order to overcome said difficulties and to 30 prevent loss of time and for the purpose of securing a substantially uninterrupted track between the elevator section and the bridge track, notwithstanding any want of alinement between the two, I combine with the 35 bridge track and elevator track section a movable or floating track section which is actuated by the elevator, and such a combination embodies the main feature of my invention.

40 It is well understood by those skilled in blast furnace practice that in order to obtain the best results in charging blast furnaces the stock when dumped from the car into the hopper of the furnace should be so delivered 45 over the apex of the bell as to be uniformly distributed around the hopper, and to accomplish this I combine with an elevated track which is centrally disposed with relation to the top of the blast furnace and its 50 hopper and bell, a hopper shaped charge distributer that is interposed between the track and the blast furnace hopper; and such a construction embodies a second feature of my invention.

55 There are other, minor, features of invention, embracing particular combinations and

special features of elemental construction, all as will hereinafter more fully appear.

In the drawings chosen for the purpose of illustrating my invention, the scope whereof is pointed out in the claims, Figure 1 is a view in side elevation of charging apparatus embodying my invention, the upper portion of a blast furnace, the bridge or charging floor leading from the hoist, the elevated track for the stock cars and the upper portion or upward extension of the hoist, being also illustrated; Fig. 2 is a plan view of the blast furnace top, the hoists and the elevated track and bridge shown in Fig. 1; Fig. 3 is 70 an enlarged view, partly in section, showing the hopper and bell of the blast furnace, means for raising and lowering the bell, the charge distributer, and the track, the stock car being illustrated in position for charging 75 the furnace; Fig. 4 is a view, partly in elevation and partly in section, of the upper portion of a blast furnace and portions of the bridge and track, the section being taken at right angles to the section shown in Fig. 3; 80 Fig. 5 is an enlarged plan view of the top of the blast furnace illustrating the relation of the distributer to the stack, the track rails being omitted; Fig. 6 is an enlarged view showing in plan one of the elevators, a portion of the bridge track, and the intermediate movable or floating track section; and Fig. 7 is an enlarged side elevation of a portion of the elevator track, a portion of the bridge track, and the interposed floating track section. 90

Like symbols refer to like parts wherever they occur.

I will now proceed to describe my invention more fully so that others skilled in the 95 art to which it appertains may apply the same.

In the drawings, A indicates the blast furnace top, B, B the hoists or elevator shafts, C the charging bridge which connects the hoists and blast furnace top, C' the bridge track which leads from the elevator to the distributer and which has its furnace end arranged over the blast furnace top, D one of the elevators, and E a movable or floating 105 track section which is interposed between the bridge track and elevator track.

The top A of the blast furnace is or may be provided with the usual hopper 1 for receiving the charge and with a suitable bell 2 110 for closing the hopper. The bell 2 is preferably suspended by links or eyebars 2^a from

an equalizing beam 3 which is itself suspended by eye-bars 3^a from an upper equalizing beam 4 that is connected by links or eye-bars 5 with suitable levers whereby the bell 2 of the hopper may be raised or lowered at the will of the operator. Such a construction so supports the bell as to leave the vertical axis of the furnace unobstructed.

The levers which support and control the bell 2 may be pivotally mounted on any suitable framing, such as F, F'. Framing G G' also erected on the top of the blast furnace supports the I-beams 6 on which are laid the track rails C', and said I-beams 6 also support the distributor 7 which latter is stayed and braced by the rods 6^a. Owing to the manner of suspending the bell 2, the track may be extended over, and disposed centrally with relation to, said bell and the hopper 1 of the blast furnace top.

7 indicates the charge distributor the function of which is to receive the charge of stock when the car is dumped and so direct it into the hopper 1 that it shall be uniformly distributed therein around the apex of the bell 2. This charge distributor 7 may be in the form of a truncated hollow cone; but is preferably in the form of a truncated hollow pyramid. It may be constructed of plates 30 braced by angle irons, and is preferably stayed by metal braces 8 secured to the I-beams 6 which form a support for those portions of the track rails C' that extend over the equalizing beam 3 and between the eye-bars 3^a. By this construction the center of the distributor 7 is brought directly under the center of the car containing the charge and directly over the apex of the bell 2, thus facilitating the uniform distribution of the charge in the hopper 1 of the blast furnace.

The charging bridge C which connects the hoists B with the blast-furnace top A may be of the usual character; but the height of the hoist above the bridge is increased so 45 that the elevator may rise above said bridge C a distance equal to, or substantially equal to, the height above the furnace hopper 1 of the distributor 7 and its supports.

The elevated bridge track C' having branches C³, C⁴, leads off from the hoist tower at the point where the elevators land, as heightened, and extends to and over the top of the blast furnace. The several tracks are supported above the bridge C by suitable 55 trestles C². Opposite the end of said track C' is located a spring buffer e, or its equivalent, which insures the proper position of the stock car with relation to the distributor 7 and hopper 1, when the movement of the stock car is arrested. This bridge track C' which is supported above the bridge C on trestles C², as before noted, may be a single 60 straight track in case a single hoist and elevator are employed; but in case twin hoists 65 are used, as commonly occurs, and as shown

in the drawings, then the main track C' will connect by means of a suitable switch with branches C³, C⁴ leading to the respective hoists B, B.

For convenience of the top-charger an elevated platform P may be provided at the switch and adjacent to the hoists B, B.

Within the elevator shafts or hoists B, B are elevators D, D each carrying an elevator track section D² on which the stock car, when loaded, is pushed from the stock floor. During the movement of the elevator the car is held in fixed position thereon by any suitable or well known means.

E indicates a section of movable or floating track which is adapted to span the gap between the elevator D and the bridge-track C', or its branches C³, C⁴, as the case may be. This movable or floating track may be of any suitable construction and manner of suspension, but is preferably devised so as to be picked up and held by the elevator on its ascent, and released when the elevator descends.

In the application of my invention illustrated in the drawings, this movable or floating track section E is shown as supported by a steel plate or plates E' hinged, as at E², to the margin of the platform P adjacent to the hoists B and B, said plate or plates projecting as at e, e into the path of the elevator D, and being reinforced by T iron stiffeners e', e', but if desired the floating rail support may be of any other desired character.

It is to be noted that in conjunction with the hereinbefore described apparatus or arrangement of tracks, hoists, &c., the stock cars employed will generally be of the side-dump pattern, as indicated by the dotted lines at 10, Fig. 3 of the drawings, and in case 105 the curved branch tracks C³, C⁴ are used with a twin hoist, as indicated in Fig. 2, it will be desirable to employ cars having flexible running gear, in order to enable said cars to run around curves of short radius.

Where there are no curves sufficiently sharp to necessitate the use of cars having a flexible wheel base, the stock cars may be bottom dumping instead of side-dumping.

The construction of the hoists, elevators, 115 tracks, floating track section, and distributor, and their arrangement relative to each other and to the top of the blast furnace, being substantially such as hereinbefore pointed out, they will, in charging the furnace, be operative as follows:

A car or tram which has been loaded on the stock floor at the foot of the hoist or elevator shaft B is locked in place on the track D² of one of the elevators D at the bottom of the 125 elevator shaft, and the top-charger by the usual means of a hoist-engine raises the load to a point above the bridge C and as near as possible to the level of the bridge track C', or its branches C³, C⁴, as the case may be. As 130

the loaded elevator approaches the level of the bridge track it picks up the section of movable or floating track E by engaging the projections e, e of the plate E', which serves 5 to make a joint between the bridge track and the elevator track D². The intervening space between the bridge track and the elevator track is thus effectually spanned, notwithstanding the elevator may be somewhat 10 above or even below the level of the bridge track. No time or labor is lost in alining the bridge track and elevator track, and the passage of the car from the elevator to the bridge track is rendered easy. The loaded 15 car is then pushed from the elevator track to one of the branches of the bridge track from which it may be switched to the main bridge-track. The loaded car passes over the latter until arrested above the distributer 7 into 20 which the charge is dumped, being uniformly distributed thereby in the hopper 1 around the apex of bell 2. The empty car is then pushed back to the elevator D and securely fastened thereon as before, after which it is 25 lowered to the stock floor for another charge. In operating twin elevators an empty car will descend on one elevator while a loaded car ascends on the other, such being the usual manner of handling the charges of a blast furnace where twin elevators are employed.

Having thus described my invention, what I claim and desire to secure by Letters Patent is:

1. In a blast furnace charging apparatus, the combination of a blast furnace having a 35 hopper and bell, a charging bridge, a horizontally disposed track elevated above the charging bridge and projecting over the blast furnace hopper, a charge distributer interposed between the elevated track and the 40 blast furnace hopper, an elevator having a track section, and a movable or floating track section interposed between the elevated bridge track and the elevator track section.

2. In a blast furnace charging apparatus, 45 the combination of a blast furnace having a hopper and bell, a charging bridge, a track elevated above the charging bridge and projecting over the blast furnace hopper, a charge distributer arranged between the ele- 50 vated track and the blast furnace hopper, and an elevator arranged adjacent to the said elevated track.

In testimony whereof I affix my signature, in presence of two subscribing witnesses.

DAVID I. MILLER.
